GARMENT

George Riedl, Aberdeen, Idaho

Application December 15, 1941, Serial No. 422,933

8 Claims. (Cl. 2—227)

This invention relates generally to improvements in garments and has particular reference to novel features of construction and arrangement in overalls for mechanics, army tank operators, and other workers who are engaged in classes of work wherein front portions of working garments such as overalls are subjected to severe wear.

One of the objects of my invention is to provide overalls which shall afford comparatively long wear under severe working conditions and which overalls shall be of a fabric base construction and provided with leather or other wear-resisting material applied to the front portions and seat portions thereof to resist wear but which wear-resisting and protective material shall be so applied to and arranged on the fabric base that the body movements of the wearer will be afforded the desired freedom to secure the desired comfort.

Another object of my invention is to provide overalls for heavy duty work and the use of which shall result in a desired economy and saving in maintenance due to my improved wear-resisting protective sectional covering which is so arranged upon the fabric base that the protective wear-resisting sectional covers are sewed, or otherwise secured, to the base fabric with suitable spaces between such cover sections disposed at the bending lines located substantially at the wearer's abdominal and groin body portions, and wherein in the lower leg sections of the protective covering are not secured to the base fabric above and below the knee portions of the fabric base but are loosely held in place at such unsecured locations by suitable adjustable straps extending from the sides of the free depending knee portions of the protective covering to the back of the knees.

Another object of my invention is found in the provision, in this type of overall of protective leather sectional coverings which are reduced to the minimum in area to add to the comfort of the wearer and to lower the cost of manufacture but without loss of the desired wear-resisting feature and wherein the abdominal wear-resisting section is provided with a suitable belt or strap portions to provide more comfort during the bending of the body of the wearer.

Still another feature of my invention resides in the provision of fabric reinforcing strips disposed on the inner face of the base fabric along the spaced portions of the protective sectional covers and which fabric reinforcing strips are secured to the base fabric by stitching or riveting same

simultaneously with the securing of the marginal edges of the protective sectional cover.

A further object of my invention resides in the inward bending of the marginal edge portions of the protective sectional covers at their adjacent spaced sides so that such marginal edges are folded between the covering and the outer face of the base fabric and sewed or otherwise secured to the base fabric as illustrated in Fig. 5 of the drawing.

A further object of my invention is to provide the garment, or overalls, with wear-resisting sectional covers which are removably secured to the fabric base by securing means of the "zipper" type.

Another object of my invention is to provide portions of the leather covered parts of the garment with a plurality of suitably spaced eyelet rivets for the dual purpose of providing additional resistance to wear and also providing ventilation to enhance the comfort feature of my invention.

With the above and other objects in view, my invention consists in the novel combination, construction and arrangement of the protective sectional covers and portions of the garment shown in preferred embodiment in the attached drawing, described in the following specification and particularly pointed out in the appended claims.

In the drawing:

Fig. 1 is a front elevational view of my improved overall embodying my invention;

Fig. 2 is a side elevation of same;

Fig. 3 is a rear elevational view of same;

Fig. 4 is an enlarged cross-section taken on line 4—4 of Fig. 1;

Fig. 5 is an enlarged cross-section similar to that shown in Fig. 4 but of a modified construction, and

Fig. 6 is an enlarged cross-section similar to Fig. 4 but showing my improved ventilating feature.

My invention includes any suitable standard type of overall of fabric generally indicated by numeral 10 and by the cross-hatching indicating the woven fabric base, and comprises the chest portion 11, the leg portions 12, preferably provided with cuffs 13, and the abdominal portion 14 between the chest and leg portions.

Side pockets are indicated by 15 and rear or hip pockets by 16. The suspenders are indicated by 17.

The fabric chest portion 11 is covered with a leather or other suitable wear-resisting cover

section 18 substantially of rectangular shape having parallel top and bottom sides respectively 18^A and 18^B and parallel sides 18^C and 18^D and the edges of the four sides are preferably stitched, as by sewing to the underlying fabric portion 14.

The bottom horizontal side 18^B of the chest covering 18 is located at substantially the bending line of the body between the chest and abdominal portions and the abdominal fabric portion 14 is provided with a leather or other suitable wear-resisting covering 19.

The top side 19^A of the abdominal cover section 19 is parallel to but spaced from the bottom side 18^B of the chest cover section 18 and the space between them is indicated by X. The inner face of the fabric base at the bending space X is preferably provided with a fabric reenforcing strip 22 extending the full length of the top side 19^A and this strip is stitched to the fabric base and the marginal portions of the chest cover section 18 and abdominal cover section 19.

The abdominal cover section 19 is cut with oppositely angularly downwardly and outwardly disposed sides parallel to the openings of the pockets 15 and preferably securely stitched to the fabric base thereat.

The bottom 19^B of the abdominal cover section 19 is disposed along the oppositely angularly disposed groin lines which extend downwardly inwardly to the crotch 20. A slit provided with a flap 19^C is provided extending upwardly from the crotch 20.

To enhance comfort and to facilitate the proper bending along the bend lines X at the upper and lower marginal sides of the abdominal cover section 19, this cover section is preferably provided with an abdominal belt having strap portions 27 secured to the opposite end portions of the cover section 19 and provided with a suitable buckle 28 for adjustably tightening such abdominal belt.

The two protective cover sections 21 for the legs are provided with upper ends 21^A disposed parallelly to the groin marginal edge 19^B of the abdominal cover section 19 but spaced therefrom as at X. At their inner upper ends, the covers 21 are cut angularly downwardly inwardly as at 21^B to eliminate any possible binding at the crotch 20.

The cover sections 21 are preferably secured at their upper ends to the fabric base as by sewing or riveting along the margins 21^A and 21^B and along their sides to points Z within 2 or 3 inches above the knee portions of the garment. The sides 21^C and 21^D of the leg portions of the cover section 21 are disposed substantially on the vertical center line of the side of the fabric leg portion.

A reenforcing fabric strip 22 may preferably be provided on the inside face of the fabric base along the space at the groin lines between the parallel adjacent margins of the abdominal and leg cover sections.

The lower end and side portions of the leg cover sections 21, extending below the knee are not attached to the fabric base, however, to prevent flopping of such loosely hung end portions, each leg cover section 21 is provided with a strap 23 having a buckle 24 whereby same may be adjustably retained below the knee.

To prolong the wear of my improved garment the same may be provided with a suitably shaped cover section 25 for the garment seat portion 75

which is stitched or otherwise secured to the fabric base.

To further enhance the utility, durability and comfort of my improved garment, the same may be provided with suitably spaced eyelet rivets 26 as shown in Figs. 1, 2 and 6. These eyelet rivets 26 may also be used to secure the protective cover sections 18, 19 and 21 to the base fabric instead of stitching same thereto or such sections 18, 19 and 21 may be detachably secured to the fabric base as by securing means known as the "zipper" type of fastening. The eyelet rivets may be arranged in any suitable manner over the areas of the protective covers to provide not only additional resistance to wear but a very desired means of ventilation.

The marginal side portion of a cover section which lies adjacent to a spaced side portion of another cover section may be bent and folded inwardly to lie between itself and the fabric overall base and such inwardly bent portion may be stitched to the overall fabric. This construction is shown in Fig. 5 and conceals the marginal securing stitches.

It is obvious that slight changes in the basic shapes of the protective cover sections 18, 19 and 21 may be readily made without departing from the spirit of my invention defined in the appended claims wherein I intend to claim my invention as broadly as the state of the art permits.

I claim:

1. A unitary garment of fabric having a chest portion, an abdominal portion and leg portions, including separate protective cover sections of a wear-resisting material different from the garment fabric secured to each of said garment portions, the marginal edges of the abdominal protective cover section being slightly spaced from the adjacent margins of the chest and leg protective cover sections, said spaced marginal edges of said sections being disposed along the lines of flexure between said portions of the body of the garment user, said cover sections for said leg portions being secured to the overall fabric at their upper ends and along their sides to a distance above the knee sections thereof whereby the lower end portions of said leg cover sections have free movement independent of the lower end portions of the garment legs, and an adjustable strap for each of said leg covers extending from the sides thereof to the back of the leg.

2. A unitary garment of fabric having a chest portion, an abdominal portion and leg portions, including separate protective cover sections of a wear-resisting material different from the garment fabric secured to each of said garment portions, the marginal edges of the abdominal protective cover section being slightly spaced

from the adjacent margins of the chest and leg protective cover sections, said spaced marginal edges of said sections being disposed along the lines of flexure between said portions of the body of the garment user, said chest and abdominal cover sections having marginal edges sewed to the fabric base, the cover sections for said leg portions sewed to the overall fabric at their upper ends and along their sides to a distance above the knee sections thereof whereby the lower end portions of said leg cover sections have free movement independent of the lower end portions of the garment legs, and fabric reenforcing strips on the inner side of the garment fabric sewed to the garment fabric and to the

70

protective cover sections along the space between marginal edges of the chest and abdominal cover sections and between the marginal edges of the abdominal cover section and the upper marginal edges of the leg cover sections.

3. A unitary overall garment of fabric comprising a chest portion, an abdominal portion and leg portions, a separate protective cover section of wear-resisting material secured to said chest portion, a separate cover section of wear-resisting material secured to said abdominal portion, and separate cover sections of wear-resisting material secured to the upper ends of said leg portions, said chest cover section extending to a slightly spaced distance from the upper marginal edge of said abdominal cover section at substantially the waist line and the lower marginal side of said abdominal cover section being disposed in a V-shape line along the groin lines, the upper marginal edges of said leg cover sections being disposed angularly downwardly inwardly in parallel alignment with but spaced from said V-shaped lower margin of said abdominal cover section, said cover sections for said leg portions each having an angularly cut upper inner corner to extend outwardly of the crotch portion of the garment, said leg cover sections being secured to the garment fabric at their upper ends and downwardly along their sides to a distance above the knee sections thereof whereby the lower end portions of said leg cover sections have free movement independent of the lower end portions of the garment legs, and reinforcing strips on the inner side of the garment fabric secured to the garment fabric and to the protective cover sections along the space between marginal edges of the chest and abdominal cover section and the upper marginal edges of the leg cover sections.

4. A unitary overall garment of fabric comprising a chest portion, an abdominal portion and leg portions, a separate protective cover section of wear-resisting material secured to said chest portion, a separate cover section of wear-resisting material secured to said abdominal portion, and separate cover sections of wear-resisting material secured to the upper ends of said leg portions, said chest cover section extending to a slightly spaced distance from the upper marginal edge of said abdominal cover section at substantially the waist line and the lower marginal side of said abdominal cover section being disposed in a V-shape line along the groin lines, the upper marginal edges of said leg cover sections being disposed angularly downwardly inwardly in parallel alignment with but spaced from said V-shaped lower margin of said abdominal cover section, and a plurality of spaced eyelet rivets in each of said chest, abdominal and leg cover sections for securing same to the garment fabric and providing ventilation therethrough.

5. A unitary garment comprising an overall of fabric having side pockets and a chest portion, an abdominal portion and leg portions; a protective cover of leather secured to said chest portion and extending from the top of said chest portion to the waist line; a protective cover of leather secured to the abdominal portion, said abdominal protective cover having an upper marginal edge spaced from the bottom marginal edge of said chest cover, sides extending to the openings of said side pockets and a bottom marginal edge cut V-shaped to lie in proximity of the groin section of the overall; and protective leather cov-

ers for the leg portions of the overall extending substantially a spaced distance from said V-shaped edge of said abdominal cover to substantially midway between the knee and the lower ends of the overall legs, said covers for said leg portions each having an angularly cut upper inner corner extending outwardly of the crotch portion of the overall, and said leg covers being secured to the overall fabric at the upper ends

10 and downwardly along their sides to a distance above the knee sections thereof whereby the lower end portions of said leg covers have free movement independent of the lower end portions of the overall fabric legs.

15 6. A unitary garment comprising an overall of fabric having side pockets and a chest portion, an abdominal portion and leg portions; a protective cover of leather secured to said chest portion and extending from the top of said chest

20 portion to the waist line; a protective cover of leather secured to the abdominal portion, said abdominal protective cover having an upper marginal edge spaced from the bottom marginal edge of said chest cover, sides extending to the openings of said side pockets and a bottom marginal edge cut V-shaped to lie in proximity of the groin section of the overall; and protective leather covers for the leg portions of the overall extending substantially a spaced distance from said

25 V-shaped edge of said abdominal cover to substantially midway between the knee and the lower ends of the overall legs, said covers for said leg portions each having an angularly cut upper inner corner extending outwardly of the crotch portion of the overall, and said leg covers being secured to the overall fabric at the upper ends and

30 downwardly along their sides to a distance above the knee sections thereof whereby the lower end portions of said leg covers have free movement

35 independent of the lower end portions of the overall fabric legs; reinforcing strips on the inner side of the overall fabric secured to the overall fabric and protective covers along the space between marginal edges of the chest and abdominal

40 covers and between the marginal edges of the abdominal cover and the upper marginal edges of the leg covers; and detachable means along the marginal edges of each of said chest, abdominal and leg covers for detachably securing said covers to the overall fabric.

7. A unitary overall garment of fabric comprising a chest portion, an abdominal portion and leg portions, a separate protective cover section of wear-resisting material secured to said chest portion, a separate cover section of wear-resisting material secured to said abdominal portion, and separate cover sections of wear-resisting material secured to the upper ends of said leg portions, said chest cover section extending to

60 a slightly spaced distance from the upper marginal edge of said abdominal cover section at substantially the waist line and the lower marginal side of said abdominal cover section being disposed in a V-shape line along the groin lines,

65 the upper marginal edges of said leg cover sections being disposed angularly downwardly inwardly in parallel alignment with but spaced from said V-shaped lower margin of said abdominal cover section, and a belt having strap portions secured to the marginal side portions of said abdominal cover section.

8. A unitary garment comprising an overall of fabric having side pockets and a chest portion, an abdominal portion and leg portions; a protective cover of leather secured to said chest por-

tion and extending from the top of said chest portion to the waist line; a protective cover of leather secured to the abdominal portion, said abdominal protective cover having an upper marginal edge spaced from the bottom marginal edge of said chest cover, sides extending to the openings of said side pockets and a bottom marginal edge cut V-shaped to lie in proximity of the groin section of the overall; and protective leather covers for the leg portions of the overall extending substantially a spaced distance from said V-shaped edge of said abdominal cover to substantially midway between the knee and the lower ends of the overall legs, said covers for said leg portions each having an angularly cut upper inner corner extending outwardly of the crotch portion of the overall, and said leg covers being secured to the overall fabric at the upper

ends and downwardly along their sides to a distance above the knee sections thereof whereby the lower end portions of said leg covers have free movement independent of the lower end portions of the overall fabric legs; reenforcing strips on the inner side of the overall fabric secured to the overall fabric and protective covers along the space between marginal edges of the chest and abdominal covers and between the marginal edges of the abdominal cover and the upper marginal edges of the leg covers; detachable eyelet rivets spaced along the marginal edges of each of said chest, abdominal and leg covers for providing ventilation through such rivets and for detachably securing said covers to the overall fabric; and a belt having strap portions secured to said abdominal cover sides.

GEORGE RIEDL.
